TELEPHONE DIAL CLEANER

Homer V. Martin, Lincoln, Nebr.

Application May 1, 1950, Serial No. 159,279

4 Claims. (Cl. 179—90)

1

This invention relates to automatic telephones and has for its principal object the provision of a simple and efficient device for cleaning dust and dirt from the arcuate surface of the stationary number plate dial under the oscillating finger wheel of the now familiar desk type call transmitter.

A further object is to provide a cleaner for such purpose having a simple holder and a wiping element readily applied and removed but held firmly in place while in use. A still further object of the invention is to provide a specially designed wiping element which can be oscillated about the stationary number plate dial, usually of plastic material, with or without simultaneous movement of the oscillating finger wheel or disk, and with or without removing the receiver from its resting place.

In the drawing:

Figure 1 is a general view of a telephone dial wiper embodying this invention and shown applied to a conventional telephone set.

Figure 2 is a plan view of the wiper.

Figure 3 shows a modified form of wiper.

Figure 4 is a section thru the cover.

Figure 5 is a central section thru the modified form.

Figure 6 is a side view of the wiper.

Figure 7 shows the method of assembly.

Figure 8 is a modified form of cleaner.

In the preferred form shown in Figures 1, 2, 4, 6 and 7 the main element is a holder 10 of plastic, metal, cardboard or any other material which would stand slight pressure, and is disposable or permanent, depending on the material used. The holder 10 includes an arcuate back 11, an upper sheet or portion 12 and a lower sheet or portion 14. The upper portion has the shape of a capstone, with radial side edges 15 and an arcuate bottom or inner margin 16 of a curvature to match the circular bead between the central card window and the usually integral annular finger wheel or disk which has ten openings corresponding with the ten numerals on the white porcelain dial just below. The upper portion 12 has a central opening 18 of about the same size as the openings in the finger wheel.

The bottom portion or arm 14 is keystone shaped, having an arcuate lower or inner margin 19 which is extended at either side by two lugs 20 projecting laterally from the radial side edge 21. These lugs provide additional cleaning surface and readily pass the usual stop member of the telephone.

The cleaning element may consist of a simple 35 need to be revolved and the cleaning unit can be

2

sheet of felt as in Figures 3, 5 and 8 but is preferably a readily detachable cover as in Figure 4 in section, the felt sheet 24 being sewed to a backing 25 of woven cloth, felt or other material 5 parallel to its arcuate inner side 27, its radial sides 28, the short portion 29 and the radial portions 30 but leaving open the outer arcuate side 31 to form a pocket for the lower arm or portion 14 of the holder 10.

10 The sewing is numbered 33 and is so spaced from the edges of the backing 25 and the cleaning material 24 to permit the two corners of the side 35 of the lug 20 to pass snugly when the holder is moved about its corner 36, between the 15 side 21 and the lug 20, as a pivot while in firm contact with the corner of the cover between the margins 29 and 30. When so assembled the cover or cleaning element remains nicely in position in use but can readily be removed for replacement by reversing the assembling step.

In Figures 3 and 5 the holder 10 is the same as before but here the cleaning element 40 is permanently or semi-permanently secured to the holder. It is shaped similarly to the bottom portion 25 of the holder 10 preferably extending slightly beyond the sides as does the removable cover 24—25. The cleaning element 40 may be of felt or other absorbent material to receive a cleaning fluid. In its cheaper form the element is glued to a papier-mâché holder and is thrown away 30 when dirty and a new unit substituted.

In the simplest form shown in Figure 8 the cleaning element alone is used. In this case the top surface 42 is roughened in any way as by the serrations 43 which are either ridges or indentations to afford purchase by the finger passing thru the zero hole of the oscillating disk. The cover 24—25 may be used in the same way.

The white porcelain of the telephone dial is 40 usually spherical and the lower portion 14 may be similarly shaped to fit the dial as shown in exaggerated form in Figure 6 but the device works very nearly as well with the portion 14 perfectly flat. It is also contemplated to make the cleaning element 40 of very thin material similar to sponge rubber in which case the cleaning element is simply cleaned when soiled as by simple washing.

When the holder with its cleaning member is 50 placed over the revolving finger wheel and revolved completely around the dial up to the finger stop the cleaning unit has covered the entire length of the white dial. When this unit is used without a finger connection, the dial does not need to be revolved and the cleaning unit can be

worked back and forth on the circumference of the revolving disk with the desired number of strokes and pressure to do the job.

What I claim is:

1. A cleaner for the dial of an automatic telephone comprising a holder having a vertical cylindrical back from the top and bottom arcuate margins of which extend in parallel relation an integral upper horizontal portion and an integral lower horizontal portion, spaced apart so that the upper portion loosely engages the top surface of the oscillating finger disk and the lower portion extends under the oscillating finger disk, and a cleaning element lying parallel to and below the lower portion and movable with the holder to lie flat against and slidily engage the number carrying dial to clean the dial as the holder is moved about the axis of the disk, with or without movement of the disk, said holder being freely oscillatable with respect to the disk.

2. The device of claim 1 in which the lower portion has two laterally extending lugs, the upper portion has a finger hole, and the cleaning element is readily detachable, having a pocket into which the two lugs may slip by a tilting motion.

3. A cleaner for the dial of a telephone comprising a holder adapted to be moved by an

operator's finger, said holder having a flat portion in the shape of a wide key-stone with a lug at each side of the bottom of the key-stone, and a cleaning element of generally similar shape consisting of a stiff sheet and a felt sheet stitched together at bottom and at both sides with the top open to form a pocket to receive said flat portion by a pivoting or tilting movement when one lug of the flat portion is inserted in one side of the cleaning element.

4. The cleaner of claim 1 in which the cleaning element is a sheet of absorbent material permanently secured to the holder and the holder is of paper stock so the cleaner may be discarded when soiled.

10 15 20 25 HOMER V. MARTIN.
